(57) **CLAIM**

The ornamental design for a wrist cellphone holder, as shown and described.

DESCRIPTION

FIG. 1 is a perspective view of a wrist cellphone holder showing my new design in use;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view.

In FIG. 1, the broken lines showing the environmental structure for purposes of illustrating the wrist cellphone holder in a condition of use. The broken lines and the structure they depict form no part of the claimed design.
